UNITED STATES PATENT OFFICE

95,725

DESIGN FOR A SHOE

Jerome Edson Andrews, Andover, Mass.

Application April 6, 1935, Serial No. 56,248

Term of patent 3½ years

To all whom it may concern:

Be it known that I, Jerome Edson Andrews, a citizen of the United States, residing at Andover, in the county of Essex and Commonwealth of Massachusetts, have invented a new, original, and ornamental Design for a Shoe, of which the following is a specification, reference being had to the accompanying drawing, forming a part thereof, in which the figure is a view in perspec-

tive of a shoe showing my design, the heel being conventional and represented in dot and dash lines, as is also the lacing.

I claim:

The ornamental design for a shoe substantially as shown and described.

In testimony whereof, I have affixed my signature hereto.

JEROME EDSON ANDREWS.
